CARBON HOLDER FOR AUTOGRAPHIC REGISTER

John E. Euth, Chicago, Ill., assignor to Uarco,
Incorporated, a corporation of Illinois

Application March 16, 1954, Serial No. 416,564

6 Claims. (Cl. 282—20)

This invention relates to a carbon holder for a writing machine and more particularly to a holder for a carbon roll in an autographic register which permits quick change of the carbon.

Autographic registers have been used for some time and some have been equipped with a roll of carbon which runs crosswise of the writing platen. These registers were so constructed that it was necessary to open the register in order to change the carbon. That also necessitated the handling of the carbon so that smudges often were a necessary part of the carbon changing as the material had to be handled by hand.

In contrast with the most usual register structures, the present device has the carbon extending from a roll supply over the platen in the same direction as the stationery. When it is desired to change the writing surface of the carbon strip, no opening of the register is required and no handling of the carbon material is necessary. The change may be effected quickly and very easily.

It is, therefore, the principal object of the present invention to provide a new mechanism for holding and changing carbon in a writing machine.

A further object is to provide a means for changing carbon in an autographic register without the necessity of opening the register to effect the change.

Another object is to provide a structure for changing carbon in an autographic register which requires no actual handling of the carbon material.

Other objects, features and advantages of the present invention will be obvious from the following description of a preferred embodiment taken in conjunction with the accompanying drawings in which:

Figure 1 is a perspective view of a new register equipped with the structure of the present invention;

Figure 2 is a fragmentary plan view, partly in section and partly broken away, showing the structure of the carbon roll holding mechanism;

Figure 3 is a fragmentary vertical sectional view through the rear portion of the register looking toward the front and toward the carbon holding structure. The cover of the register is shown in partially open position and one of the carbon holders is shown in dotted outline, partially swung out of usable position;

Figure 4 is a fragmentary sectional view through one end of one carbon holder;

Figure 5 is a fragmentary vertical sectional view looking toward the carbon holders from the bottom side of Figure 2;

Figure 6 is a view similar to Figure 5, taken through the center portion of the carbon holders;

Figure 7 is a fragmentary vertical sectional view looking toward the carbon holders from the upper side of Figure 2;

Figure 8 is a fragmentary horizontal sectional view through the carbon holders and taken substantially along line 8—8 in Figure 5;

Figure 9 is a fragmentary vertical sectional view taken

2

substantially along line 9—9 in Figure 8 showing one cam adjacent a holder; and

Figure 10 is a fragmentary vertical sectional view of the cam operating handle taken substantially along line 10—10 in Figure 8.

The particular register chosen for illustration is one having a base 11 in which a supply of stationery in zigzag form is placed. The upper portion 12 of the register comprises a lid which may be hinged to the base along one marginal side. A catch release 13 on the opposite side may secure the lid 12 to the base 11.

The lid 12 is formed with an opening 14 through which forms 15 may appear for writing purposes. These forms rest upon a platen 16 supported on the base 11 so as to be positioned closely adjacent the opening. An operating handle 17 is connected with a pin type feed 18 for advancing the forms over the platen. A pivoted door 19 on the front of the lid may be opened to admit a file copy of the forms to a record compartment under the platen.

The path of the stationery from the base 11 upwardly over the platen 16 may best be seen in Figures 2 and 6. The lower stationery strip 20 passes from the supply directly over the platen 16. The carbon holders are positioned side by side and extend across the register on the rear side of the platen. Each holder is made to receive a carbon roll R so that a strip of carbon material may be placed over the platen between each of the record stationery strips. Thus, the next strip 21 extends around the first holder and then over the platen so that the carbon strip S will be interposed between the first record strip 20 and second strip 21. In the particular embodiment shown, four stationery strips pass over the platen and three carbon strips are interleaved with the record strips. The superposed strips may pass under a guide blade 28 on one side of the platen while a pin type feed may engage perforations in a feed band on the opposite side of the stationery strips. The carbon strips are narrower than the stationery by an amount equal to the width of the feed bands so that the carbon is not engaged by the feed pins.

The structure of each carbon holder is such that it holds a roll of carbon material against advancement over the platen when the stationery is advanced by the feeding means in the register. When the carbon becomes worn so that it should be replaced, a mechanism is provided to permit the rolls to turn in the holders allowing the carbon to feed through the register and over the platen with the stationery strips. The particular structure of the holder which permits this function is one of simple but effective design. Each holder has a rounded body 30 secured by detents 31 in a left-hand end plate 32 and by similar detents 33 in a right-hand end plate 34. The rounded body 30 comprises a semicircle in cross section so that the forwardly facing portion of the body is open.

The end plate 32 is provided with an aperture 35 connected to the forward edge 36 of the plate by a slot 37 slightly narrower than the opening. Outwardly extending ears 38 at the lower edges of the plate serve to support the left-hand end of the holder on a platform 39. A stop 40 at the rear of the platform 39 holds all of the plates in abutting side by side position between the stop and the rear portion 41 supporting the plates.

The opposite end plates 34 are formed with a central aperture 42. These plates are provided on their lower edges with pairs of ears 43 similar to the ears 38 except that they are pierced to receive a shaft 44 secured in stationary position in a pair of brackets 45. In this manner the holders are pivotally secured to the reg-

ister so that each holder may be swung upwardly as indicated in the dotted lines of Figure 3.

The carbon roll R is held in the holder on a spindle 46 having a blunt end 47 for insertion through the aperture 42 in the right-hand end plates 34. A thimble 48 is slidingly mounted on the opposite end of the spindle and held against removal by a screw 49. The thimble is urged toward the end of the spindle by a compression spring 50 connected to the spindle.

The spring 50 aids in retaining the spindle in the holder when a roll of carbon is placed on the spindle. Each spindle has a disk 51 spaced from the opposite end plate 34 a distance such that it will be in contact with the roll when the spindle is placed in the holder. Thus, a carbon roll equipped with a core 52 may be passed over enlarged portions 53 on the spindle and then the spindle may be inserted in the holder by placing the blunt end 47 in the aperture 42, bringing the end of the roll into contact with the end plate 34. By continuing this movement after the contact of the roll and the plate, the spring 50 may be compressed moving the spindle through the roll until the disk 51 hits the opposite end. At this point, the thimble cannot be passed through the slot 37 because it is too wide at the point which would strike the opening to the slot. However, the thimble is slidingly mounted so that upon further compression of the spring 50, the narrow portion 54 of the thimble may be aligned with the slot so as to pass through the slot and into the enlarged opening 35. Thereafter, the spring 50 urges the thimble outwardly and maintains the spindle in a position to hold the disk 51 against the end of the carbon roll. By this simple structure, the single spring 50 can serve to hold the spindle in the holder and also frictionally bind the roll against turning on the spindle.

When the carbon becomes worn to an extent that it should be changed, the operator of the register need only release the tension of the disks against the rolls so that they may turn, allowing the carbon to move forwardly with the stationery over the platen. A simple mechanism mounted in the lid 12 is provided to accomplish this purpose. A thumb piece 55 is connected to a cam shaft 56 upon which is mounted a plurality of cams 57, one opposite each spindle. Upon turning of the shaft, the cams come in contact with the blunt ends 47 of the spindles, moving them to the left in the holders, thus compressing the spring 50 and moving the disks 51 away from the rolls as illustrated in Figure 8. Coil spring 58 urges the cam shaft to a position of rest, holding the cams away from the spindles, however, the cams will stay in contact with the spindles without manually holding the thumb piece, due to the illustrated shape of the cams. A small detent 59 on the underside of the finger piece 55 may travel in an arcuate slot 60 in the casing to limit turning movement of the thumb piece and shaft 56.

When the carbon rolls are released from the frictional holding accomplished by the disks on the spindles, the friction between the superposed carbon strips and stationery strips may be enough to pull the carbon forwardly and discharge a form length from the register. Should this friction between the strips be insufficient, slight hand pressure can be placed by the operator on the superposed strips in the area over the platen to insure that the carbon is advanced with the stationery. If desired, suitable mechanical means may be provided for applying the light pressure in place of hand pressure. When a form length is torn from the strips, the carbon strips are likewise severed and may be discarded. A new sheet of carbon will be maintained in place by a reverse rotation of the thumb piece 55 to again apply the tension and friction hold on the carbon rolls. The structure is particularly effective in that rolls of carbon of approximately 40 ft. in length can be supplied so

that the carbon need only be replenished after extended use.

The form of the carbon holders is such that the body provides a very good guide for leading the stationery strips around each holder. Very little chance of difficulty is presented by the structure.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. In an autographic register having means for moving, superposed record and carbon strips over a writing surface, a carbon roll holder having spaced end plates and a joining body plate extending across the register, a spindle extending movably through the holder end plates and removably secured therein for receiving a carbon roll, means yieldably urging the spindle in one direction within the holder, bearing means on the spindle for frictionally gripping a carbon roll under action of said yieldable means to prevent the roll from turning on the spindle; and manually operable means mounted in the register in position for moving said spindle in the holder in opposition to said yieldable means to release the frictionally gripping bearing means from the carbon roll to permit advance of carbon over the writing surface.

2. In an autographic register having a casing and a cover thereon, a carbon roll holder mounted on said casing and extending across the register, a spindle movably extending through the holder and removably secured therein, a disk secured to said spindle for bearing against one end of a carbon roll placed on the spindle; spring means yieldingly urging the spindle and disk toward one end of the holder to frictionally clamp a carbon roll between one end of the holder and the disk restraining the roll from turning on the spindle; and a manually shiftable cam member mounted in said register cover opposite an end of the spindle for moving the spindle longitudinally in the holder to release said carbon roll permitting advance of carbon from the roll.

3. A carbon holder for use in an autographic register, comprising: a holder body having spaced apertured end plates and a joining body plate; a spindle movably and removably mounted in the apertures for receiving a roll of carbon paper; a disk on the spindle and spring means urging the disk and spindle in one direction in the holder to frictionally clamp a carbon roll in the holder against turning; and a cam member mounted adjacent one end of the spindle for moving the spindle in opposition to said spring and releasing a carbon roll therein for turning on the spindle.

4. A carbon holder as specified in claim 3 wherein said cam member and carbon holder are both mounted in an autographic register casing and the cam member is provided with an operating handle exteriorly of the register casing.

5. An autographic register, comprising: a casing having a writing platen; a plurality of carbon roll holders mounted side by side across the casing rearwardly of the platen, each holder having end plates and a movable spindle removably held in the plates for receiving a carbon roll; a disk on each spindle and spring means engaging the disk urging the disk and spindle in one direction in the holder so as to frictionally clamp a carbon roll between one plate and the disk when mounted on the spindle; a cam member mounted in said register casing opposite an end of each spindle for moving the spindles in said holders and in opposition to said spring urging to release the frictional gripping of the carbon rolls; and an exposed handle member connected with said cams for manually effecting said movement of the cams and spindles as desired.

6. An autographic register as specified in claim 5

wherein each spindle is provided with a slideable thimble thereon urged toward one end by said spring, said thimble having an enlarged portion resiliently urged into seating in the base of a keyhole-shaped slot provided in one of the end plates for cooperation with the thimble in removably locking the spindle in the holder. 5
